UNITED STATES PATENT OFFICE.

DONALD R. MCKILLICAN, OF NEW YORK, N. Y., ASSIGNOR TO MECHANICAL MIXERS CORPORATION, OF NEW YORK, N. Y., A CORPORATION OF DELAWARE.

METHOD OF MIXING.

Application filed February 25, 1922. Serial No. 539,200.

To all whom it may concern:

Be it known that I, DONALD R. MCKILLICAN, a citizen of the United States, residing in the city of New York, county of New York, and State of New York, have invented a new and useful Improvement in Methods of Mixing, of which the following is a specification.

My invention relates broadly to methods for the intimate mixing of substances in general, more particularly to the mixing of food products, and specifically to the mixing of soda fountain drinks.

Reference is made to my co-pending applications for agitators, Serial No. 440,293, filed January 27th, 1921, shrouded agitators, Serial No. 459,238, filed April 7th, 1921, and drink mixers, Serial No. 473,738, filed May 31st, 1921, which show and claim forms of apparatus capable of performing my improved methods of mixing when operated within the particular speed limits required. The process however may also be performed in other apparatus.

25 Referring to the accompanying drawings:

Fig. 1 is a central vertical section of a soda fountain shaker cup containing a mix, taken on the line 1—1 of Fig. 2, looking in the direction of the arrows; and

30 Fig. 2 is a vertical section of the same, taken on the line 2—2 of Fig. 1.

The numeral 1 indicates the shaker cup, 2 the agitator shaft driven in the direction of the arrow 3 and carrying the agitator 4 35 within the shaker cup 1.

My improved methods of mixing have been only recently observed through a special experimental glass shaker cup by operating it partly filled with water, and 40 watching the flow of the small bubbles entrained with the moving water. Particles of cork have been placed in the moving water and drops of ink have also been introduced at various places in the water to aid 45 its visibility.

In Figs. 1 and 2, I indicate the motion of the water, thus observed, by means of arrows. The portion of the water which appears solid is indicated by light diagonal 50 cross-section lines, as at 10, rather than by the conventional indication for liquid, which might impair the visibility of the arrows.

The arrows 20—21, where they indicate the motion of the water at the surface 55 nearest the observer, are solid. The arrows

30—31, where they indicate the motion of the water at the wall of the shaker cup remote from the observer, are dotted. The arrows 40—41, where they indicate the motion of the water flowing from a distance toward the observer; then at the surface and then away from the observer, are indicated with dotted heads and tails and solid bodies. The arrows 50—51, which indicate the motion of the water from a distance toward the observer and then at the surface, are indicated with solid heads and dotted tails.

60 The motion of the water, and probably opaque liquids, the motion in which cannot be observed, such for instance as milk containing powdered malted milk, ice cream etc. is very complex and changes in details of the cycle of motion of the mix, make specific description impracticable beyond such description as can be expressed in the 65 form of a drawing provided with arrows.

70 There are a few general and clearly marked phenomena in my method of mixing; for instance, the vortex 60, having its axis bent from the vertical to the horizontal, 75 with its lower extremity extending to the center of the agitator 4, which is probably induced by the motion of the agitator 4 around a horizontal axis and the mounting of the agitator 4 at one side and at the bottom 80 of the shaker cup 1, allowing only a limited bottom clearance. The flow indicated by the full arrows 21 around the periphery of the agitator 4 in Fig. 2, and the full arrows 20 in the vortex 60, in both 85 Figs. 1 and 2; is also conspicuous.

90 One of the prominent differences in the mixing performed in my method when operated within its normal speed range and in correctly designed apparatus, as compared 95 with agitation performed in an apparatus of the conventional type with a vertical shaft, is that the mix appears to flow freely into the agitator 4, whereas in the vertical shaft type of mixer cavitation occurs at the agitator when run at high speeds. On the other hand, in the horizontal shaft type of mixers shown in the references cited in the above-mentioned applications the occurrence of a 100 vortex is not even suggested and a vortex 105 leading toward the center of the agitator 4 is necessary for the best mixing to permit the lighter parts of the mix to descend promptly to the agitator.

An interesting feature of my method is 110

the manner in which a part of the mix is centrifugally projected away from the periphery of the agitator 4, while another part of the mix flows toward the center of agitation.

It is difficult to express, or even observe, the motion of a tumultuously agitated mix and variations in my method continuously occur during the cycle of operation. With 10 various constituents in the mix and variation in the mixing apparatus and speed of operation the cycle is again modified, but the foregoing description is intended to be diagrammatic and instructive, so that those 15 skilled in the art may practice my improved method effectively.

I do not limit myself to the precise method described and my invention may be developed with progress of the art. The 20 particular factors of my method which I desire to secure by Letters Patent are defined and measured in the appended claims.

I claim:

1. The method of mixing, which consists 25 of rotating and mixing a portion of a mix around an axis other than vertical and producing a vortex in another portion of the mix, with a curved axis substantially con-

centric with the first mentioned axis at its lower end and substantially vertical at its 30 upper end.

2. The method of mixing which consists of mixing part of a mix at a laterally extending axis, impelling another part of the mix around the axis and deflecting the latter 35 part to induce a vortex around an upwardly extending axis having its lower end at the laterally extending axis.

3. The method of mixing, which consists of mixing one portion and centrifugally 40 projecting another portion of a mix at a horizontal axis, deflecting the projected portion and thus inducing a hollow vortex having a vertical axis extending at its lower end to the horizontal axis, so that light 45 constituents of the mix may descend within the vortex to the horizontal axis for mixing.

4. The method of mixing, which consists of impelling and mixing part of a mix around a horizontal axis, thereby inducing 50 movement in the remainder of the mix and the formation of a vertical depression having the approximate shape of a hollow cone with its base at the top of the mix and its apex at the horizontal axis.

DONALD R. MCKILLICAN.
